BOBBIN WINDING MACHINE

Roland Heeley, Beverly, Mass., assignor to United
Shoe Machinery Corporation, Flemington, N. J.,
a corporation of New Jersey

Application September 2, 1949, Serial No. 113,799

1 Claim. (Cl. 242—23)

1

The present invention relates to improvements in machines for winding sewing machine bobbins and is herein illustrated as embodied in a winding machine of the type disclosed in United States Letters Patent No. 2,343,935, granted March 14, 1944, on application of Paul W. Senfleben, in which a horizontal bobbin winding spindle and a mandrel supporting a series of empty bobbins are rotated and advanced step by step through a series of winding operations to fill the bobbins successively, all the bobbins being rotated together and being projected further and further outwardly of the machine as the winding operations progress.

The primary objects of the present invention are to provide a simply constructed and efficiently operated support for the end of the bobbin carrying mandrel and to prevent vibration of the mandrel as it is projected from a machine of the type referred to. Other objects are to provide a support which will not interfere with the removal or replacement of the bobbins on the mandrel and which will steady the mandrel and otherwise to improve the operation of the machine.

In accordance with these objects, the principal feature of the invention resides in a bobbin winding machine having a rotatable spindle, a fixed bearing through which the spindle projects, a removable mandrel secured at one end to the projecting end of the spindle to support a plurality of bobbins in end-to-end relation, a thread guide acting to direct the thread to a bobbin on the mandrel and step-by-step mechanism for actuating the spindle lengthwise a distance equal to the length of a bobbin to cause the mandrel to project further and further from the machine after each bobbin is filled with thread, a bearing being movable with the mandrel for steadyng the mandrel at the end thereof opposite the spindle, said bearing sliding along a stationary guide rod and along a parallel guide bar to prevent swinging movement of the bearing on the rod and the guide bar terminating short of the rod to enable the bearing to be swung on the rod clear of the mandrel, in which there is provided friction means to hold the bearing temporarily clear of the mandrel comprising an arcuate member on the rod and a spring clip on the bearing engaging the arcuate member.

These and other features of the invention consist of the novel constructions, combinations and arrangements of parts hereinafter described and claimed as will more fully be understood

2

from the following specification taken in connection with the accompanying drawings, in which

Fig. 1 is a view in front elevation of the winding head of a bobbin winding machine embodying the present invention, showing the parts surrounding the winding spindle and illustrating the positions of the parts as a series of winding operations is started;

Fig. 2 is a view in front elevation on an enlarged scale of one end of the winding spindle and bobbin supporting mandrel in the machine of Fig. 1, showing the construction of the steadyng bearing with the mandrel in its outmost projected position before being forced into the machine preparatory to initiating a series of winding operations;

Fig. 3 is a plan view of the parts shown in Fig. 2;

Fig. 4 is a sectional view taken along the line IV—IV of Fig. 2; and

Fig. 5 is an end view of the parts shown in Fig. 2.

The winding machine disclosed herein is provided with a rotating winding spindle 10 having attached thereto a removable mandrel 12 for supporting a series of sewing machine bobbins 14 in aligned, end-to-end relation to each other. The spindle is rotated to fill the bobbins on the mandrel with thread, the thread being directed to each bobbin successively over a suitable guide comprising a stripper 16 for a wax pot 18. As soon as the first bobbin of a series on the mandrel is filled with thread a thread controller 20 is actuated away from that bobbin and step-by-step mechanism is thrown into operation for actuating the spindle lengthwise outwardly in a progressive manner a distance equal to the length of a bobbin on the mandrel to bring a new empty bobbin into winding position. The mechanism for actuating the spindle lengthwise includes a bushing 22, in which the spindle 10 rotates but with which the spindle moves lengthwise. The bushing 22 is pivotally connected with the upper end of a link 24 connected in turn at its mid portion with a chain 26 passing over a pulley 28 and supporting at its lower end a weight 30. To control the lengthwise movements of the spindle the lower end of the link 24 is pivotally connected to a ratchet bar 32 engaged by a detent 34 actuated by the thread controller 20.

As the winding operations of the machine progress from the first bobbin on the spindle to the final bobbin it is apparent that the mandrel

is projected further and further out from the machine frame with each operation. To guide the advancing end of the spindle in the patent machine the flanges of the bobbins 14 are surrounded by a tubular bearing 36 (see Figs. 2 and 4) fixed in the frame of the machine. This tubular bearing is effective to steady the bobbins while the mandrel is in its fully inserted position of Fig. 1. As the spindle moves the mandrel outwardly, however, into the position of Fig. 2, the distance from the outer end of the mandrel to the bearing 36 is increased. Accordingly, there is a greater possibility of vibration and erratic movement in the free end of the spindle during its rotation.

To steady the mandrel at the outer end thereof and to supplement the support given by the bearing 36 to the flanges on the bobbins, the outer end of the mandrel is rotatable in a movable bearing in the form of a bushing 38 supported on a sliding mounting. The sliding mounting consists of a carrier 40 having a passage through which extends a stationary rod 42 arranged parallel to the mandrel. The rod 42 is mounted in an opening in the machine frame and is clamped in position by a set screw 44 threaded into the machine frame. During lengthwise movement of the mandrel 12 the carrier 40 slides along the rod 42 lengthwise of the rod, being forced outwardly by the mandrel step by step as each bobbin is filled with thread.

To prevent axial displacement of the steadyng bearing 38 from the end of the mandrel a releasable securing means is provided in the bearing comprising a yielding spring-pressed plunger 46 which enters a circular groove 48 in the end of the mandrel. The arrangement is such that the steadyng bearing may be freed by disengagement from the mandrel in preparation for its removal from the spindle to enable replacement of the mandrel after all the bobbins thereon are filled with thread.

After the steadyng bearing has been disengaged and freed from the mandrel the carrier 40 is swung about the rod 42 to a horizontal position shown in the dot-dash lines of Fig. 5 to clear the end of the mandrel so that the mandrel can be readily removed or replaced on the spindle. Swinging movement of the carrier on the rod can take place only when the carrier is moved to the end of the rod.

To prevent swinging movement of the carrier on the rod in positions along the rod other than at its end and to maintain alinement of the bearing 38 with the end of the mandrel there is mounted on the machine frame in parallel relation to the rod at a location just above it a separate stationary bar 49 engaging a notched surface on the carrier. The bar terminates sufficiently short of the end of the rod to enable the carrier to be swung on the end of the rod without engaging the bar. As soon as the carrier is moved inwardly of the machine from the end of the rod, however, the bar prevents swinging movement of the carrier.

To retain the steadyng bearing in horizontal position on the end of the guide rod when the carrier is swung to clear the winding mandrel, according to the illustrated invention, there is secured to the free end of the rod 42 an arcuate segmental disk 50, the outer surface of which is concentric with the rod except for the lower cut-away portion of the disk. The carrier 40 has a

spring clip 52 attached thereto for yielding engagement with the concentric surface of the disk when the carrier is moved to the end of the rod 42. Thus, during operation of the machine the winding mandrel moves the carrier to the end of the bar 49 without disengaging it from the bar. The carrier thereafter is manually disengaged from the bar by movement to the end of the rod, a handle 54 being provided on the carrier to facilitate such disengagement. As soon as the carrier is moved to the end of the rod 42 it may be swung to clear the mandrel.

To avoid difficulty with particles of wax collecting on the rod 44 thrown off by the thread as it is being wound upon a bobbin, there is fixedly secured to the machine frame above the bobbin while in winding position an L-shaped guard plate 56 having its base portion projecting over the bobbin as it reaches the winding position between the mandrel and the rod 42. The guard plate catches the wax particles thrown off the thread and prevents their adherence to the rod. Thus, by use of a short guard plate, the entire length of the rod is kept clean and easy sliding movement of the bearing on the rod is insured in all positions.

The nature and scope of the invention having been indicated and a particular embodiment having been described, what is claimed is:

30. A bobbin winding machine having a rotatable and reciprocable spindle, a fixed bearing for the spindle, a removable mandrel secured at one end to the end of the spindle projecting from the bearing to support a plurality of bobbins in end-to-end relation, a thread guide acting to direct thread to a bobbin on the spindle, and step-by-step mechanism for actuating the spindle lengthwise through its bearing a distance between successive bobbins after each bobbin is filled with thread, in combination with a bearing for steadyng the mandrel at the end thereof opposite the spindle, a stationary guide rod on which the steadyng bearing is mounted for swinging movement to clear the mandrel in preparation for its removal from the spindle and a separate bar engaged with the bearing and arranged parallel to the rod to prevent swinging movement of the bearing but terminating short of the end of the rod to enable the bearing to swing on the rod clear of the end of the mandrel, and friction means on the rod to hold the bearing clear of the mandrel, comprising an arcuate member on the rod and a spring clip on the bearing arranged to engage the arcuate member when the bearing is disengaged from the mandrel.

ROLAND HEELEY.
